United States Patent Office

Des. 212,978
Patented Dec. 17, 1968

212,978

MANUALLY OPERATED ADDING MACHINE

Thomas McGourty, P.O. Box 134,
Norfolk, Conn. 06058

Filed Oct. 24, 1967, Ser. No. 9,145

Term of patent 3½ years

(Cl. D64—11)

FIG. 1 is a perspective view, viewed from the front of a manually operated adding machine showing my new design; and

FIG. 2 is a perspective view, viewed from the rear.

The essential features of the design reside in the portions shown in solid lines; conventional details being shown in broken lines. The bottom surface of the design is plain.

I claim:

The ornamental design for a manually operated adding machine, as shown and described.
